SPOON OR SIMILAR ARTICLE

Isadore Albert Lipman, Meriden, Conn.

Application May 23, 1956, Serial No. 41,607

Term of patent 14 years

(Cl. D54—12)

Fig. 1.

Fig. 2.

Fig. 3.

Fig. 1 is a front elevation of the spoon. Fig. 2 is a side elevation of the spoon. Fig. 3 is a rear elevation of the spoon.

The essential features of my design reside in the configuration of the handle in combination with the particular ornamentation.

I claim:

The ornamental design for a spoon or similar article, as shown and described.
